DRAWING PRESS

Alidor Lefere, Jackson, Mich., assignor to Lefere
Forge & Machine Company, Jackson, Mich., a
corporation of Michigan

Application April 30, 1941, Serial No. 391,083

3 Claims. (Cl. 29—33)

1

The present invention relates to drawing presses, and more particularly to a construction for impressing the outside of a drawn blank to shape the same as desired.

The present invention is for the purpose of performing one of the steps in the method of making high explosive shells and like tubular members having one closed end and one open end, disclosed in my copending application Serial No. 391,084, filed April 30, 1941, and now Patent No. 2,338,652, granted Jan. 4, 1944. The disclosure of aforesaid application includes a step of drawing of forged blanks. Since the forging dies become worn after periods of use, the outside of the closed end of a shell-like member loses its original sharpness. According to the present invention, a machine is provided which operates so that as the forged blank is drawn, the drawing mandrel urges the drawn blank against a resiliently mounted die to impress the outside of the closed end to shape it. Also, the impressing die is provided with numbers or letters by means of which the heat number may be impressed into the end of the drawn blank to identify the same.

An object of the present invention is to employ a drawing mandrel in a drawing machine to force a blank being drawn thereby against a yieldably mounted impressing die.

Another object of the invention is to impress a piece of work by forcing the work against a yieldably mounted die.

These and other objects residing in the arrangement, combination and construction of the parts will be apparent from the following specification when taken with the accompanying drawing, in which

Fig. 1 is a vertical section of a drawing press according to the present invention,

Fig. 2 is a partial section of the construction of Fig. 1 taken on the line II—II of Fig. 1,

Fig. 3 is a section on the line III—III of Fig. 1, and

Fig. 4 is a view taken along the line IV—IV of Fig. 1.

Referring particularly to the drawing, the reference character 1 indicates the ram of a drawing press, the ram being reciprocable by such conventional mechanism as, for instance, a piston and cylinder, not shown. The ram has supported therein a mandrel support 2, the support 2 having a ball head 3 mounted in a socket 4 in the ram 1. The lower portion 5 of the socket 4 is associated with a sleeve 6 having an open side 7 therein, shown particularly in Fig. 2. The support 2 has connected thereto a drawing mandrel 8. The

2

open side 7 of the sleeve 6 permits the support 2 and mandrel 8 to swing outwardly, as shown in Fig. 2. The support 2 has connected thereto a rod 9, shown particularly in Fig. 2, on the outer end of which is a counterbalancing weight 10. The length of the rod 9 and the weight of the counterbalancing weight 10 are such that the weight 10 swings the mandrel 8 out to its dotted line position shown in Fig. 2 into a position for receiving work thereon.

Pivoted to the bottom face 15 of the sleeve 6 by a pin 16 is an angulated arm 17. The arm 17 is urged about the pin 16, as viewed in Fig. 3, in a counterclockwise direction by a spring 18 having one end thereof connected to the arm 17 and the other end thereof connected to a portion of the machine frame, not shown. The arm 17 has projecting therefrom on the opposite side of the pin 16 from the spring 18, a nose portion 19 which is arranged to hold the mandrel support 2 in vertical position. The arm 17 is provided adjacent the nose 19 with a follower surface 20, against which the mandrel support 2 bears on being swung toward its upright position to cam the arm 17 about its pin 16 to permit the return of the mandrel support 2 to its upright position. When the mandrel 8 and its support 2 are in upright position, the tension of the spring 18 is great enough to overcome the tendency of the weight 10 to swing the mandrel 8 and its support 2 away from their upright positions.

Associated with the ram 1 and the drawing mandrel 8 is a press bed 21 from which a platform 23 is supported by legs 22. Arranged on the platform 23 is a drawing die 24 and a trimming die 25, the trimming die 25 being for the purpose of cutting off the flash from the outside of the blank to be drawn, when the same is formed by forging. Axially slidably in suitable guideways in the platform 23 is a pair of stripper bars 26. Each of the stripper bars 26 is connected to a bar 27, the bars 27 extending along opposite sides of the platform 23. The free ends of the bars 27 are connected by helical springs 28 extending along opposite sides of the platform 23 at right angles to the bars 27 and parallel to the stripper bars 26. The purpose of the stripper bars 26 is to yield laterally as work is forced past the drawing die 24 and to move inwardly under the action of the springs 28 when the work has moved past them so as to bear against the top edge of the work as the drawing mandrel 8 is returned to its upper position to strip the work from the drawing mandrel 8.

Arranged immediately beneath the drawing die

24 is a support 31 having therein an impressing die 32. The impression die 32 has therein removable numbering and lettering dies 33, as shown more particularly in Figs. 1 and 4. The support 31 is resiliently mounted through helical springs 34 bearing against a base 35, which is in turn mounted on the bed 21.

In operation a hot blank 36 is disposed on the mandrel 8 when it is in its dotted outline position disclosed in Fig. 2. Preferably the blank 36 is disposed on the mandrel 8 directly from the forging dies by which it is shaped, while still having its forging heat. The mandrel 8 is disposed in its dotted outline position by pivoting the arm 17 by means of the handle 37 about the pin 16, to move the nose 19 away from its position against the mandrel support 2. The counterbalancing weight 10 then swings the mandrel 8 forwardly about the ball 3 of the mandrel support 2. When the blank 36 has been placed on the forwardly extending mandrel 8, it is swung into its upright position camming the arm 17 about the pin 16 by bearing against the follower face 20 of the arm 17. As soon as the mandrel support 2 is in its upright position, the spring 18 swings the arm 17 about its pin 16 to bring the nose 19 into position to hold the mandrel support 2 in its upright position. The machine is then actuated to move the ram 4 downwardly. It will be understood that as soon as the mandrel 8 is moved to its upright position, the blank 36 falls downwardly until it rests in the trimming die 25. As the mandrel 8 is moved downwardly it engages with the inside of the bottom of the blank 36 and forces the blank 36 downwardly while the trimming die 25 trims off the flash 38 on the blank 36, and the drawing die swings the sides of the blank 36 inwardly to provide a cylindrical blank 39, shown in dotted outline in Fig. 1.

As the blank 39 is moved past the stripper bars 26, the bars 26 slide laterally against the action of the springs 28. When the blank 39 has moved completely past the stripper bars 26, they move inwardly under the action of the springs 28 to the position shown in Fig. 1. Just before the mandrel 8 reaches its lowermost position it moves the closed end of the blank 39 into engagement with the impressing die 32. The die 32 is shaped as it is desired to have the finished shape of the end of the blank 39, and is also provided with the removable numbers and letters 33 to impress on the bottom of the blank 39 the number of the heat which is being run, or other desired information. The die 32 is not intended to be of such configuration as to substantially alter the form of the outside of the closed bottom of the blank 36, but is merely intended to correctly shape the same to overcome any inaccuracies that may have arisen due to the wearing of the forging dies which formed the blank 36. As the mandrel 8 moves further downwardly forcing the blank 39 against the die 32, the springs 34 yield. It will, of course, be understood that the springs 34 must offer sufficient resistance to overcome the resistance to being impressed offered by the blank 39 so that the die 32 will actually make an impression on the outside of the closed end of the blank 39. The resiliency offered by the springs 34 prevents the mandrel 8 from upsetting as it forces the blank 39 against the die 32.

When the outside of the closed end of the blank 39 has been impressed by the die 32, the mandrel 8 is moved upwardly. Since the blank 39 will adhere to the mandrel 8, the stripping bars 26 are employed to overhang the upper edge of the blank 39 to strip it from the mandrel 8 during the up-

ward movement of the mandrel 8. The blank 39 then falls down into the die 32 from which it is removed by slightly elevating the blank 39 and then swinging the bottom thereof outwardly and then bodily removing the blank from the press.

The swinging mandrel employed mounted for swinging about the ball 3 in the socket 4 is particularly advantageous in the drawing operation, for the reason that the slow moving ram is enabled to travel a much shorter path than would be necessary if the mandrel 8 were not swingable and had to be sufficiently high in order to permit the placing of the blank 36 thereover at an elevated position. By making the mandrel 8 swingable, it is possible to place the blank 36 on the mandrel 8, to swing back the mandrel 8 into its upright position, close to the dies 24 and 25 and to bring the mandrel 8 and blank 36 into operative relation with the dies 25 and 24 in less time than would be possible if the blank 36 were placed on the mandrel 8 at an elevated position.

While the invention has been described in connection with a step in the making of high explosive shells disclosed in my aforesaid copending application, it will be understood that the invention is of broader scope and that it may be applied to other types of work. For example, while one of the most important features of the invention is the combining of the impressing die with a drawing press, it is contemplated that the idea of impressing work against a resiliently mounted die may be used in association with other types of presses than drawing presses. Also, while the particular machine employed is designed for drawing blanks having a flash which is trimmed off by the trimming die 25, it will be understood that the trimming of the flash is not an essential feature of the present invention since the blanks drawn may not have a flash.

Having thus described my invention, what I desire to secure by Letters Patent and claim is:

1. In a drawing press, an axially vertically movable mandrel for receiving thereon a piece of work open at one end, a drawing die through which the work is forced by said die to draw the work, a stripper associated with said mandrel, operative upon return movement of said mandrel, an impressing die in the path of movement of the work moved by said mandrel, a resilient support for said impressing die, whereby said work is moved by said mandrel through said drawing die into engagement with said impressing die to impress the same, the resistance offered by said support being great enough to overcome the resistance to being impressed offered by the work, said impressing die being so arranged that following withdrawal of the mandrel and stripping of the work therefrom, said impressing die constitutes a support on which the work remains by gravity, and an annular support concentric with, adjacent and beneath said stripper for maintaining the top of the work against lateral movement while supported on said die.

2. In a drawing press, an axially vertically movable mandrel for receiving thereon a piece of work open at one end, a drawing die through which the work is forced by said die to draw the work, a press bed, a platform, means resiliently supporting said platform from and above said bed, a stripper associated with said mandrel, operative upon return movement of said mandrel, an impressing die mounted on said platform, said impressing die being in the path of movement of the work moved by said mandrel, whereby said work is moved by said mandrel through said drawing die into engagement with said impress-

ing die to impress the same, the resistance offered by said supporting means being great enough to overcome the resistance to being impressed offered by the work, said impressing die being so arranged that following withdrawing of the mandrel and stripping of the work therefrom, said impressing die constitutes a support on which the work remains by gravity, and an annular support concentric with, adjacent and beneath said stripper for maintaining the top of the work against lateral movement while supported on said die.

3. In a metal drawing press, an axially movable mandrel for receiving thereon a piece of work open at one end, a drawing die through

which work is forced by said mandrel to draw the work, a press bed, a plurality of spaced helical springs supported on end from said bed, a platform supported on the upper ends of said springs, and an impressing die mounted on said platform, said impressing die being in the path of movement of the work moved by said mandrel whereby said work is moved by said mandrel through said drawing die and into engagement with said impressing die to impress the same, the resistance offered by said springs being great enough to overcome the resistance to being impressed offered by the work.

ALIDOR LEFERE.
